US00D984067S

(12) **United States Design Patent** (10) **Patent No.:** **US D984,067 S**
Wang et al. (45) **Date of Patent:** **** Apr. 18, 2023**

(54) **TOY FOR ANIMALS**

(71) Applicant: **Guangdong Vking Intelligent Technology Co., Ltd.**, Guangdong (CN)

(72) Inventors: **Yungao Wang**, Guangdong (CN); **Yuejing Wang**, Guangdong (CN)

(73) Assignee: **GUANGDONG VKING INTELLIGENT TECHNOLOGY CO., LTD.**, Guangdong (CN)

(**) Term: **15 Years**

(21) Appl. No.: **29/788,736**

(22) Filed: **Jul. 23, 2021**

(30) **Foreign Application Priority Data**

May 20, 2021 (CN) 202130303719.3

(51) LOC (14) Cl. **30-12**

(52) U.S. Cl. **D30/160**
USPC .....

(58) **Field of Classification Search**

USPC **D30/160, 199**

CPC **A01K 15/025; A01K 15/026**

See application file for complete search history.
